Patented February 7, 1905.

UNITED STATES PATENT OFFICE.

KIRKE B. MATHES, OF BATAVIA, NEW YORK, ASSIGNOR TO THE MINOR-MATHES COMPANY, OF BATAVIA, NEW YORK.

DESIGN FOR A SHOE-DISPLAY STAND.

SPECIFICATION forming part of Design No. 37,329, dated February 7, 1905.

Application filed December 13, 1904. Serial No. 236,760. Term of patent 3½ years.

To all whom it may concern:

Be it known that I, KIRKE B. MATHES, a citizen of the United States, residing at Batavia, in the county of Genesee and State of New York, have invented a new, original, and ornamental Design for a Shoe-Display Stand, of which the following is a specification, reference being had to the accompanying drawings, forming a part thereof.

10 In the accompanying drawings, Figure 1 is a view in front elevation, and Fig. 2 is a view

in side elevation, showing my design for a shoe-display stand.

What I claim as new, and desire to secure by Letters Patent, is—

15 The ornamental design for a shoe-display stand, as shown.

KIRKE B. MATHES.
